UNITED STATES PATENT OFFICE.

ALBERT BRUCKNER, OF ETNA, PENNSYLVANIA.

IMITATION WALL AND TILE CONSTRUCTION.

1,147,704.

Specification of Letters Patent.

Patented July 27, 1915.

Application filed September 26, 1914. Serial No. 883,653.

To all whom it may concern:

Be it known that I, ALBERT BRUCKNER, a citizen of the United States, residing at Etna, in the county of Allegheny and State of Pennsylvania, have invented new and useful Improvements in Imitation Wall and Tile Construction, of which the following is a specification.

My invention relates to wall and tile construction.

10 The objects of my invention are to make it possible to construct wall facings and tile facings with different parts of the facings finished differently in a very simple, cheap, and efficient manner.

15 Referring to the accompanying drawings, Figure 1 is a rear elevation of a frame-work made in accordance with my invention; Fig. 2, a section of Fig. 1 on the line II—II; Fig. 20 3, a vertical section of a wall and the said frame-work, showing how my invention is applied to a wall, a portion of the wall facing being already made; Fig. 4, a front elevation of a wall facing made by my invention; Fig. 5, a top plan view of a frame-work 25 for making facings independently of the wall to which they are to be applied; Fig. 6, a section of Fig. 5 on the line VI—VI; and Fig. 7, a face view of a group of imitation tile faces made by the frame-work shown on Figs. 5 and 6. Fig. 4 shows a portion of a wall face comprising five imitation blocks each having a rectangular face 1 in relief surrounded at each side by the beveled edges 30 2. The beveled edges of the adjacent blocks forms V-shaped grooves in imitation of the grooves between adjacent blocks in stone walls. The horizontal grooves are continuous while the vertical grooves between adjacent blocks terminate opposite the middle of the blocks above and below the said adjacent blocks, in imitation of the usual manner of breaking joints.

35 To construct a wall-face having the rectangular faces and the V-shaped grooves therein as shown on Fig. 4, I prefer to proceed as follows: I construct a frame-work or mold plate 3 which may be simply a plane wall made of boards, on which are arranged the plane or flat backed cleats or ribs 4, their cross-section being a right angled triangle. The cleats are arranged in groups of four. Each group of four cleats forming a rectangular frame constituting with the inclosed 40 portion of the mold plate 3 a mold for one imitation block. The cleats have one of

their sides adjacent to their right angle in contact with the mold plate 3 to which they are nailed with preferably finishing nails 5 having their hoods driven into the cleats and their pointed ends projecting through the plate so that pliers may seize the said ends and pull the nails through the cleats and frame. The cleat frames are arranged in rows with the sides of consecutive rows being in contact and the ends of the frames in each row also in contact, the remaining sides of the cleats adjacent to their right angles being on contact, whereby the contiguous cleats have the same cross-section as the grooves between consecutive faces 1. The joints between the ends of contiguous frames are midway between the joints at the ends of the frames above and below.

50 The mold wall comprising the mold plate 3 and the cleats or ribs nailed thereto and arranged as described and as shown on Figs. 1, 2, and 3 is set up in a vertical position before the wall 6 to which the imitation facing is to be applied (Fig. 3) with the 55 cleats facing the wall 6 and spaced a short distance therefrom. The material 7, such as cement or concrete, in a plastic or wet state is poured into the mold-space between the wall 6 and the mold-plate 3. When the 60 material 7 has set it adheres to the wall 6 and its outer face permanently takes the relief form imposed by the mold-plate and cleats. After the material has set sufficiently, the nails 5 are drawn by pliers or 65 other suitable device outwardly through the cleat and mold-plate; and the latter is removed leaving the cleats in the V-shaped 70 grooves between the relief faces 1. These faces are then treated with any suitable fluid 75 material, such as cement, plaster, mortar, coloring, and the like, to give them any desired surface finish.

80 I have shown the faces 1 figured or roughened. This may be accomplished by applying cement, concrete, or the like thereto of any desired color and making the same have any desired surface appearance. This can be done without marring or changing the surface of the beveled edges 2, as the same are 85 protected by the cleats. After the faces 1 have been finished, the cleats 4 are removed, whereupon the bottoms of the V-shaped 90 grooves may be striped or otherwise treated to imitate mortar between the imitation 95 blocks.

95 Referring now to Figs. 5, 6, and 7, I pro-

vide the horizontal mold-plate 3' to which the cleats or ribs 4' are secured in the same arrangement as the cleats 4 are secured to the mold plate 3. The nails 5' may be 5 driven through the mold plate and into the cleats, which in this form of my invention may be permanently secured to the mold plate; but these nails may be made removable or other suitable devices be substituted.

10 Shallow channels 8 are made in the outer angles of contiguous cleats. Colored mortar or cement or other plastic material 9 is placed in these grooves to form beads 10 between contiguous blocks or tiles 11 (Fig. 15 7). After the material 9 has set, the mold plate 3' with the cleats 4' thereon may be used in the manner described with respect to the plate 3 and cleats 4, except that the plate and cleats are removed together from 20 the wall face cast in contact therewith. The plate 3' and the cleats 4' thereon with the material 9 in the grooves 8 may remain as shown on Fig. 5 with the cleats 4' projecting upwardly. Cement or the like may 25 be poured over the plate and cleats and beads 9 so that the several imitation blocks cast shall be united by a backing 10 as shown on the left hand part of Fig. 6. After the cement has set, the mold plate is 30 turned bottom side up, when it can be readily stripped from the wall or tile facing. This facing can then be secured to walls in any suitable manner. The ribs on Figs. 1, 2, and 3 may have the groove 8, if desired.

35 I claim—

1. In a mold for making wall and tile facings with multiple relief surfaces thereon, a mold-plate against which the said relief surfaces may be cast, ribs arranged on the said 40 mold-plate to form depressions between adjacent relief surfaces when the facings are cast in contact with the mold-plate and ribs,

and detachable means connecting the ribs and the mold-plate whereby the mold-plate may be removed leaving the ribs between the relief surfaces of the facings, the said mold plate being extended so as to cover several of the said relief surfaces.

2. In a mold for making wall and tile facings with multiple relief surfaces thereon, a mold-plate against which the said relief surfaces may be cast, ribs arranged on the said mold-plate to form depressions between adjacent relief surfaces when the facings are cast in contact with the mold-plate and ribs, and means whereby the ribs may be secured to the mold-plate and nails extending through the mold-plate into the ribs, and beyond the outer face of the mold-plate for detachably securing the mold-plate and the ribs together, the said mold plate being extended so as to cover several of the said relief surfaces.

3. In a mold for making wall and tile facings with multiple relief surfaces thereon, a plane mold-plate against which the said relief surfaces may be cast, plane-backed ribs arranged on the said mold-plate to form depressions between adjacent relief surfaces when the facings are cast in contact with the mold-plate and ribs, and means whereby the ribs may be secured to the mold-plate and the mold-plate may be removed leaving the ribs between the relief surfaces of the facings, the said mold plate being extended so as to cover several of the said relief surfaces.

Signed at Pittsburgh this 23rd day of September, 1914.

ALBERT BRUCKNER.
